UNITED STATES PATENT OFFICE.

NORVELL R. WYATT, OF GRANDVIEW, MISSOURI.

NON-REFILLABLE BOTTLE.

1,164,442.

Specification of Letters Patent. Patented Dec. 14, 1915.

Application filed May 22, 1914. Serial No. 840,262.

To all whom it may concern:

Be it known that I, NORVELL R. WYATT, a citizen of the United States, residing at Grandview, in the county of Jackson and State of Missouri, have invented certain new and useful Improvements in Non-Refillable Bottles, of which the following is a specification.

This invention relates to non-refillable bottles the primary object of which is to positively preclude reuse of the bottle unless the neck, or at least a portion thereof has been severed from the bottle, preventing the selling of a spurious liquid under the same name as that of the original manufacturer, or analogous fraudulent reuses.

Another object is to provide a comparatively inexpensive bottle which although preventing refilling, will permit of the expeditious dispensing of the contents of the bottle when desired.

Other objects as well as the nature, characteristic features and scope of my invention will be more readily understood from the following description taken in connection with the accompanying drawings and pointed out in the claim forming a part of this specification.

Referring to the drawings:—Figure 1 is a longitudinal sectional view of a bottle neck constructed in accordance with my invention showing the stopper mounted therein; Fig. 2 is a cross sectional view taken on the line 2—2 of Fig. 1; Fig. 3 is a perspective view of the stopper, and Fig. 4 is an elevational view of the valve chamber.

In the drawings wherein is illustrated the preferred embodiment of this invention a portion of a bottle body 5 is provided which has issuing therefrom a bottle neck 6, the latter in the present instance having its inner terminal constricted as indicated at 7 and provided adjacent its outer end with diametrically opposite depressions 8 to provide parallel recesses, the outer end of the bottle being provided with the usual bead.

Mounted in the neck 6 is a stopper 9 which in the present instance is preferably of a cylindrical configuration and has formed on its outer periphery a plurality of equidistant longitudinally extending ribs 10 so as to provide fluid-ways 11, said ribs 10 being extended below the lower end of the stopper whereby communication is had with the interior of the stopper. Enlarged ribs 12 are formed on opposite sides of the stop-

per 9 and are provided with elongated slots or recesses 13 which register with the depressions or recesses 8 in the bottle neck 6. The upper portion 14 of the stopper 9 as shown to advantage in Fig. 1 is solid while the lower end is tubular for a purpose presently appearing.

Mounted in the bottle neck 6 is a valve chamber 15 in the present instance comprising a conical base 16 which has mounted thereon a rubber sleeve 17, said sleeve engaging with the constricted portion 7 of the bottle neck, the base 16 having a tubular portion 18 extending upwardly therefrom, being of a diameter relatively smaller than the upper end of said base, the portion 18 provided in its upper margin with a plurality of recesses 19 which communicate with the ways 11 of the stopper 9. The lower inner periphery of the base 16 is enlarged and inclined as indicated at 20 to provide a valve seat, it being thus far seen that communication is open through the valve chamber 15 and the stopper 14 so as to permit of the free dispensing of the contents of the bottle.

Mounted for movement in the valve chamber 15 is a ball valve 21 which is normally held in engagement with the valve seat 20 by an elastic element 22 the latter in the present instance comprising a coil spring. The convolution on one end of said spring is in engagement with the inner face of the enlarged portion 14 of the stopper 9 while the opposite end is in engagement with a guide sleeve 23, said sleeve having a plurality of arms 24 extending therefrom. The outer terminals of said arms are slidably engaged with the inner periphery of the chamber 15 to prevent lateral thrust of the spring 22 and positively seat the valve 21 on its base. Refilling of the bottle is thereby prevented but at the same time expeditious dispensing of the contents of the bottle is permitted, since by merely inverting the latter it is seen that the pressure on the interior of the bottle will be sufficient to overcome the resistance of the elastic element 22 thereby forcing the valve from its seat and opening communication through the valve chamber 15 and the stopper 14, subsequently permitting the contents to be dispensed.

In order to fixedly engage the stopper 9 in the neck 6, flat springs 25 are provided which are folded and engaged in the openings or recesses 13 of the stopper 9 so that

- when the stopper is inserted in the bottle neck the springs will automatically expand into the recesses 8 in the bottle neck when the springs reach this point.
- 5 In operation, to dispense the contents of the bottle, the latter is inverted permitting the valve 21 to be unseated by pressure of the liquid on the interior of the bottle. Communication is thereby opened through 10 the valve chamber 15 permitting the liquid to flow through the V-shaped openings 19 and through the openings in the bottom of the stopper 9, which are provided by extending the ribs 10, the liquid subsequently 15 issuing through the ways 11. It is seen that refilling of the bottle is positively prevented since even should the bottle be laid on its side and placed in a receptacle of water or the like, which is frequently done in order 20 to refill bottles, the valve 21 will remain intact since it is necessary that the bottle be inverted in view of the fact that the contents of the bottle must be such as to overcome the resistance of the spring 22 for 25 opening communication. It is likewise obvious that the insertion of wires or the like for unseating the valve is positively prevented in view of the peculiar formation of stopper and valve chamber.
- 30 It will be understood that the above description and accompanying drawings comprehend only the general and preferred embodiment of my invention and that various

minor changes in details of construction, proportion and arrangement of parts, may 35 be made within the scope of the appended claim and without sacrificing any of the advantages of my invention.

Having thus fully described my invention, what I claim as new and desire to secure by 40 Letters Patent, is:—

In combination with a bottle having a neck issuing therefrom, a means for preventing the refilling of said bottle including a chamber snugly engaged with the inner periphery of said neck and provided with an opening therein, the diameter of the lower end of which gradually decreases, a valve 45 mounted for movement in said opening to close communication through the latter, said valve being unseated by the pressure of the liquid on the interior of the bottle when the latter is inverted, a spring to normally hold 50 said valve in a closed position adjacent the lower terminal of said opening, a stopper mounted in said neck and abutting the outer end of said spring to prevent displacement 55 of the latter, said stopper likewise preventing the introduction of means into said neck for unseating said valve.

In testimony whereof I affix my signature in presence of two witnesses.

NORVELL R. WYATT.
